UNITED STATES PATENT OFFICE.

WILEY P. TIBBITS, OF CHARLESTON, SOUTH CAROLINA.

LIFE-PRESERVER.

1,390,474.

Specification of Letters Patent. Patented Sept. 13, 1921.

Application filed May 25, 1920. Serial No. 384,052.

To all whom it may concern:

Be it known that I, WILEY P. TIBBITS, a citizen of the United States, residing at Charleston, in the county of Charleston and 5 State of South Carolina, have invented certain new and useful Improvements in Life-Preservers, of which the following is a specification.

This invention relates to improvements in 10 life saving garments and has as its primary object to provide a garment embodying a novel arrangement of air chambers which are normally deflated but which may be readily inflated, and which garment, when 15 upon the person, will serve to sustain one in a substantially upright position in the water whether in cases of emergency or when one is learning to swim.

One of the important objects of the invention 20 is to so arrange the air chambers of the device as to insure of a substantially upright position being maintained so that one's head cannot become submerged for any appreciable length of time.

Another object of the invention is to so 25 construct the device that while the air chambers extend beneath the arms and circumferentially of the trunk, the wearer of the device may have a desired freedom of limb 30 movement so that he may propel himself in the water.

A further object of the invention is to provide in a device of the class mentioned embodying inflatable air chambers, means for 35 inclosing and somewhat restricting the air chambers when they are inflated so as to prevent over inflation and likewise protect the air chambers and prevent the escape of air should they become punctured through 40 contact with pins worn about the clothing.

Another object of the invention is to so 45 construct and proportion and arrange the air chambers that the device as a whole will possess a greater degree of buoyancy at its upper portion than at its lower portion so as to effectually perform its function of maintaining the head of the wearer above water.

Another important object of the invention 50 is to so construct the device that it may be readily adjusted as to size thus adapting a standard size of the device to be fitted to

persons having relatively widely varying chest and waist measurements.

In the accompanying drawings: 55

Figure 1 is a perspective view illustrating one form of the device in use;

Fig. 2 is a detail vertical sectional view on the line 2—2 of Fig. 1;

Fig. 3 is a top plan view of the pair of 60 trunks employed when the device is made use of as a bathing suit and illustrating the manner in which the trunks may be adjusted as to size;

Fig. 4 is a view in elevation looking at the 65 inner side of the upper garment of the device, parts being broken away and parts being shown in section;

Fig. 5 is a detail view partly in elevation and partly in section illustrating one form 70 of valve for employment in connection with the inflating tubes for the air chamber of the inflating device;

Fig. 6 is a similar view illustrating a modified and simplified form of valve; 75

Fig. 7 is a view similar to Fig. 1 illustrating a modified form of device;

Fig. 8 is a detail vertical sectional view on the line 8—8 of Fig. 7;

Fig. 9 is a view similar to Fig. 4 illustrating the form of the invention shown in 80 Figs. 7 and 8.

Figs. 1 to 4 inclusive illustrate a form of the invention which is especially designed for use by one learning to swim and comprises, in combination, an upper body garment and a pair of trunks. The form of the invention shown in Figs. 7, 8 and 9 is illustrated as comprising the upper garment only and is more particularly designed for 85 use as a life preserver in an emergency. It will be understood, however, that the latter form may be employed in combination with a pair of trunks and that on the other hand the form of the invention shown in Figs. 1, 90 2 and 4 may be employed as an emergency life preserving device independently of the trunks which are illustrated in combination therewith.

The upper garment, in the form of the 100 invention shown in Figs. 1 to 4 inclusive, is indicated in general by the numeral 1 and the same resembles in many respects an ordinary vest, being open at its front and being

provided with shoulder portions 2 which define arm openings 3 and which are to be passed over the shoulders of the person upon whom the garment is fitted.

5 The body portion of the garment 1 is indicated in general by the numeral 4 and the upper portion, which embodies the shoulder portions 2, is indicated in general by the numeral 5. The body portion 4 is preferably made up from two pieces of cloth between the upper edges of which is disposed the lower edge of the upper portion 5 of the garment, these edges being hemmed and suitably stitched or otherwise united as indicated by the numeral 6, the seam thus formed extending circumferentially of the garment as a whole. Parallel to this seam and at suitably spaced intervals, the two plies of the body portion 4 of the garment, of which the inner ply is indicated by the numeral 7 and the outer ply by the numeral 8, are united by parallel lines of stitching 9 which extend circumferentially of the said body portion of the garment. Likewise the lower edges of the inner and outer plies 7 and 8 are united by lines of stitching 10. Thus there is formed in the body portion of the garment a series of circumferentially extending pockets 11, 12, 13 and 14, there being 20 four such pockets in the present instance although it will be understood that the number of pockets may be increased or decreased as found desirable. The plies 7 and 8 are further united at their vertical edges as indicated by the numerals 15 and 16 so that when the garment is fitted to the person, the front portion 15 may overlap the front portion 16. In that form of the invention now being described, the portion 15 is formed 25 with a vertically extending series of button-holes 17 to receive buttons upon the opposite front portion 16 of the garment. These buttons are preferably arranged in a plurality of vertical rows, one row, located substantially at the edge of the portion 16, being indicated by the numeral 18, and other rows 30 19 and 20 being arranged parallel to the first mentioned row but, in the order designated, being spaced increasing distances inwardly 35 of the said vertical edge of the front of the garment. Thus if the garment is applied to a stout person the row of buttons 18 may be engaged through the buttonholes 17, or if the garment would fit too loose when thus applied, the edge portion 15 may be caused to overlap to a greater extent the edge portion 16, and either the buttons 19 or the buttons 20 may be engaged through the buttonholes 17. In this manner the garment may 40 be adapted to more or less snugly fit persons having different chest measurements. It will be understood, of course, that more than three rows of buttons may be provided or less than that number.

65 By reference to Fig. 4 of the drawings it

will be observed that the pockets 11, 12, 13 and 14 extend the entire width of the garment. Arranged within each of these pockets is an air chamber preferably in the nature of a rubber tube, and these air chambers are indicated respectively by the numerals 21, 22, 23 and 24. The pocket 11 is the uppermost pocket and the pocket 14 is the lowermost pocket of the series, the pocket 12 being located below the pocket 11 75 and above the pocket 13. The air chambers 21 and 22 are of substantially the same capacity as are also the air chambers 23 and 24 but preferably the air chambers 21 and 22 are of greater capacity than the chambers 23 80 and 24, and in practice the chamber 21 will be fully inflated while the air chamber 22 will be not quite so fully inflated. Likewise the air chamber 23 will be substantially fully inflated but the chamber 24 will not 85 be so fully inflated as the chamber 23. Thus the air chambers will be of increasing buoyancy from the lowermost chamber of the series to the uppermost chamber so that as a consequence the head and shoulders of the 90 one wearing the garment will be most effectively sustained above water and the body will be supported substantially in an upright position.

The pockets 11, 12, 13 and 14 are proportioned in accordance with the difference in size between the several air chambers or tubes which they are to receive and house but one feature of the invention resides in forming each pocket, as regards its vertical 100 dimensions, of somewhat smaller size than the respective tube or air chamber which is contained therein so that when the air chambers are inflated they will be somewhat restricted and thus prevented from being 105 overinflated, and at the same time the cloth pockets, when wet by water, will so snugly fit the respective air chambers as to prevent or at least materially retard the escape of air in the event of a small puncture such as 110 might be occasioned by a pin in the clothing.

In order that each of the air chambers may be inflated or deflated independently of the others, each chamber is provided with an inflating tube 25 preferably of rubber and placed in communication with the interior of the chamber in any suitable manner. Fitted into the end of this tube is an inflating check valve which may be of the form shown in Fig. 5 of the drawings in 120 which figure the numeral 26 indicates the valve casing provided between its ends with a diaphragm 27 the under side of which constitutes a valve seat indicated by the numeral 28, this diaphragm having a central opening 29 through which extends the upper portion of the stem 30 of the valve which is indicated in general by the numeral 31. A disk or facing 32 of rubber or any other material suitable for the purpose is 125 130

provided upon the upper face of the valve body 31 so as to insure of an air-tight engagement of the valve against its seat. The upper extremity of the valve stem 30 projects beyond the upper or outer end of the casing 26 and may be provided with a knob or enlargement 33 against which pressure may be exerted for the purpose of moving the valve to open position. The lower portion of the stem of the valve is indicated by the numeral 34 and a spring 35 is fitted onto this portion of the stem and bears at its upper or outer end against the valve body 31 and at its opposite end against a plug 36 which is threaded or fitted in any other suitable manner removably into the inner end of the casing 36 and is provided with a central opening 37 through which the said lower portion 34 of the valve stem may work. This plug is also provided with one or more air ports 38. The valve casing 28 is fitted at its last mentioned end into the outer end of the respective inflating tube 25 and secured in any suitable manner as for example by wire wrapping the end of the tube. In inflating the air chamber the outer or exposed end of the valve casing is placed in the mouth and air is blown through the casing and past the valve and into the respective air chamber, the valve opening with the pressure and immediately closing so as to trap the injected air. The inflating tubes 25 leading from the several air chambers may extend to the exterior of the respective pockets at any convenient points and in any desired manner but are preferably arranged so that they will all be readily accessible when the garment is fitted to the person so that in the event of deflation or partial deflation of any of the air chambers, the same may be conveniently re-inflated.

Fig. 6 of the drawings illustrates a modified form of inflating tube, the tube in this figure being indicated by the numeral 39 and being adapted to be closed by a tapered plug 40 which may be connected with the tube by a suitable flexible element 41. In using this form of sealing device for the tube the tube will, of course, be pinched after each injection of air into the air chamber, and after the chamber has been inflated, the plug 40 will be fitted into place.

As before stated this form of the invention comprises, in addition to the upper garment 1, a pair of trunks which are most clearly illustrated in Figs. 1, 2 and 3 of the drawings and indicated in general by the numeral 42. These trunks at the waist-line are provided with a row of buttons 43 which are adapted to be fitted through buttonholes 44 formed in a flap or apron 45 which is stitched or otherwise secured at its upper edge to the inner side of the garment 1 near the lower edge thereof and substantially

at the waist-line. One side of the trunks at the front may be brought to position overlapping the opposite side of the front as clearly shown in Fig. 3 of the drawings, the first mentioned side being provided with a buttonhole 46 to receive the buttons 43 selectively. Thus the first mentioned side of the tongues may be buttoned to the opposite side thereof selectively at differently spaced points so as to adapt the waist portion of a standard size of the trunks to fit persons having different waist measurements. In order to further provide for adjustment of the trunks at the waist-line, and also to provide means whereby the leg portions of the trunks may be made smaller or larger, the trunks are provided at each side with a vertical series of snap or similar fasteners, one member of each fastener being indicated by the numeral 47 and the other member by the numeral 48. When it is desired to restrict the waist portion of the trunks and also the leg portions, the fastening elements may be engaged with each other, the opposite sides of the trunks being lapped or folded for this purpose, and on the other hand the trunks may be increased in size by disengaging the fastening elements from each other.

In that form of the invention shown in Figs. 7, 8, and 9, the body garment is indicated in general by the numeral 49 and inasmuch as it is substantially identical with the form previously described, it will only be necessary to point out such slight differences as exist. In this form of the invention the two plies comprising the body of the garment are united as in the first described form, to provide pockets, the dividing lines of stitching being indicated by the numeral 50. However, in this form the lines of stitching 50 extend from one side of the open front of the garment to a point spaced inwardly from the opposite side of the said front as indicated by the numeral 51, and instead of providing an independent air chamber in each pocket, each air chamber comprises a tube 52 which is folded between its ends so that one-half will lie within an upper pocket and the other half within the pocket next below it, the tube at its bend extending through the space provided by stopping the line of stitching 50 short of the last mentioned side of the front of the garment, as indicated by the numeral 53.

Also in this form of the invention, instead of the buttons and buttonholes provided in the first described form for closing the front of the garment, I may make use of tongue and hasp fasteners the tongue members of which are indicated by the numeral 54 and the hasp members by the numeral 55. Otherwise the arrangement is the same and the garment is employed in precisely the same manner as is the one first described. Also in this form all of the air chambers may

be of the same dimensions as also all of the pockets.

While I have specifically described the use of buttons and buttonholes and tongue and hasp fasteners, it will be understood that I may employ any type of devices for closing the garment such for example as snap fasteners, hooks and eyes or the like.

With the device of the present invention applied, should the wearer be in an upright posture in the water, and should he desire to assume the usual swimming posture, it is only necessary for him to bend or incline his neck and head forwardly. If on the other hand he desires to swim on his back or float, it is only necessary for him to incline his head in a rearward direction. If the wearer is in the ordinary swimming posture and desires to assume an upright position in the water it is only necessary for him to raise his head in an upward and rearward direction, and if he is swimming on his back and desires to assume an upright position it is only necessary to raise the head in a forward direction.

It will be understood that while the air chambers 21, 22, 23 and 24 may be inflated to different pressures as previously explained, it will be understood that if it becomes necessary to obtain a greater buoyancy, all of these air chambers may be fully inflated.

Having thus described the invention, what is claimed as new is:

1. In a device of the class described, a garment provided with an open front and having the side portions of its front adapted

to be overlapped to a greater or less extent, closing means upon the overlapping side of the front, a plurality of closing means upon the overlapped side of the front spaced at varying distances from the edge of the said side, and an inflatable air chamber extending circumferentially of the garment.

2. In a device of the class described, an upper garment provided with a series of circumferential pockets located one above another with the lowermost pocket extending substantially at the waistline, inflatable air chambers housed within the pockets, an attaching flap upon the inner side of the garment inwardly of the said lowermost air chamber, and extending longitudinally with relation thereto, a lower garment, and means for connecting the said flap with the waist portion of the lower garment.

3. In a device of the class described, an upper garment open at its front and provided with means for closing the said front selectively along lines spaced varying distances from one side of the open front, the garment having a circumferential pocket terminating at its ends adjacent the said open front, an inflatable chamber in the pocket, a lower garment, means for connecting the garments substantially at their waist-lines, the lower garment having an open front, and means for closing the open front of the lower garment selectively along lines spaced varying distances from one side of the said open front thereof.

In testimony whereof I affix my signature.

WILEY P. TIBBITS. [L.S.]
